UNITED STATES PATENT OFFICE

110,907

DESIGN FOR A COMBINED DESK, TABLE, AND UTILITY CABINET

Dorothy E. Patz, New York, N. Y.

Application May 27, 1938, Serial No. 77,435

Term of patent 14 years

To all whom it may concern:

Be it known that I, Dorothy E. Patz, a citizen of the United States, residing at New York, in the county of New York and State of New York, have invented a new, original, and ornamental Design for a Combined Desk, Table, and Utility Cabinet, of which the following is a specification, reference being had to the accompanying drawing, forming a part thereof.

In the drawing:

I claim:

The ornamental design for a combined desk, table, and utility cabinet, as shown.

DOROTHY E. PATZ.
